(57) **CLAIM**

The ornamental design for a penlight, as shown and described.

DESCRIPTION

FIG. 1 is a top, front, right side perspective view of a penlight showing our new design;

FIG. 2 is a front elevation view thereof;

FIG. 3 is a rear elevation view thereof;

FIG. 4 is a right side elevation view thereof, the left side elevation view being a mirror image;

FIG. 5 is a top plan view thereof; and,

FIG. 6 is a bottom plan view thereof.

The broken lines shown in the drawings represent unclaimed environment and are for illustrative purposes only, forming no part of the claimed design.
